UNITED STATES PATENT OFFICE.

BRUNO V. NORDBERG, OF MILWAUKEE, WISCONSIN.

VARIABLE-CAPACITY PUMP.

1,032,421.

Specification of Letters Patent. Patented July 16, 1912.

Application filed January 21, 1909. Serial No. 473,416.

To all whom it may concern:

Be it known that I, BRUNO V. NORDBERG, a citizen of the United States, residing at Milwaukee, in the county of Milwaukee and State of Wisconsin, have invented certain new and useful Improvements in Variable-Capacity Pumps, of which the following is a specification, reference being had to the accompanying drawing, forming a part 10 thereof.

This invention relates more particularly to pumps actuated by substantially constant speed motors and designed to operate upon inelastic fluids or liquids such as water, under varying demands. Its main objects are to vary the capacity of such a pump and the consumption of power required for its operation according to variations in the demand upon it without changing its speed; 20 hence to economize power, and generally to improve the construction and operation of pumps of this class.

It consists in the construction, arrangement and combination of parts as hereinabove particularly described and claimed.

In the accompanying drawing like characters designate the same parts in the several figures.

Figure 1 is a vertical longitudinal section 30 of a pump embodying the invention; Fig. 2 is an enlarged end view as seen from the left with relation to Fig. 1 of the valve mechanism controlling the operation of the hydraulic motor; Fig. 3 is an enlarged side elevation as viewed from the right with relation to Fig. 2 of such mechanism; Fig. 4 is an inverted horizontal section on a still larger scale of a part of the valve mechanism, the plane of the section and the direction of view being indicated by the dotted line 4-4 and arrows on Fig. 2; Fig. 5 is a vertical section on the line 5-5, Figs. 4 and 6; Fig. 6 is a vertical cross section on the line 6-6, Figs. 4, 5, 7 and 8; Fig. 7 is a section on the line 7-7, Fig. 6; Fig. 8 is a corresponding section on the line 8-8, Fig. 6; Fig. 9 is a section on the line 9-9, Fig. 6; Fig. 10 is a similar but inverted section on the line 10-10, Fig. 6; and Fig. 11 is a horizontal section on the line 11-11, Fig. 1.

Referring to Fig. 1, which for the pur-

pose of illustration shows a part of a center-packed duplex plunger pump, although the invention is equally applicable to and may be embodied in other kinds of pumps, *a* 55 designates the pump cylinder, in the present case made in two parts or sections which are provided with suitable suction and discharge valves (not shown), *b* a reciprocating plunger working through stuffing boxes 60 in the inner ends of the cylinder sections, *c* a rotary shaft provided with a driving crank or eccentric *d* for each plunger *b*, and *e* a countershaft from which in the present instance, the crank shaft is driven through 65 a pinion *f*, indicated by a dotted line, and a gear *g*.

The plunger *b* has an adjustable power transmitting connection with the crank or eccentric *d* for varying the stroke of 70 the plunger in accordance with variations in the load or demand upon the pump. Such connection consists of a pitman or rod *h* connected at one end with the crank *d* and at the other end with links *i* and *j* which are 75 of the same length and are connected at their opposite ends with the rod of the plunger *b* through a cross head *k*, and with a rocker or adjustable fulcrum support *l* respectively. In the present case the rocker 80 consists of a pair of triangular arms corresponding in length on one side with the links *i* and *j* and each provided at its upper angle with a horizontal pin or journal *m* by which they are pivotally connected with 85 the pump frame. To balance the driving connections of the plunger and to evenly distribute the strains, the links *i* and *j* are duplicated and arranged on both sides of the pitman *h* and cross head *k*, the links *j* 90 being pivoted at their lower ends to the inner sides of the rocker arms, which may be connected with each other by cross rods *l'* or otherwise.

The construction and arrangement of the 95 parts are such that when the plunger *b* is at mid stroke the pivot *n* between the pitman *h* and the links *i* and *j* will be in line with the pivots *m* of the rocker *l*, and when the pivots *o* between the links *j* and the 100 rocker *l* are brought into line with the pivot *p* between the links *i* and the cross head *k*,

the plunger *b* will remain motionless while the driving crank *d* continues to turn.

For adjusting the rocker *l* to vary the stroke of the plunger as required, a motor is provided. For this purpose a hydraulic motor comprising a cylinder *q* and reciprocating piston *r* is shown, the cylinder being made in two parts and the piston, which is of the center-packed plunger type, working through glands in the inner ends of the cylinder sections and provided in the space between them with a cross head *s* which is connected on each side by a link or rod *t* with the rocker *l* at the outer lower angles of its arms, as shown in Fig. 11. A motor operated by inelastic fluid is employed, in order that in the adjustment of the rocker its movement and position may be predetermined with accuracy, a result difficult if not impossible to attain with a direct connected elastic fluid motor.

The outer ends of the motor cylinder *q* are connected by pipes *u* and *v*, as shown in Figs. 1 and 11, with passages *w* and *x*, in a valve case *y*, as shown in Figs. 5, 7, 8, 9 and 10. The case *y* is formed with four parallel cylindrical chambers in which are fitted bushings *z*, containing two admission valves 2 and 3, and two exhaust valves 4 and 5. Each of the bushings *z* is formed with two chambers 6 and 7, with an intervening port and valve seat to which the associated valve is fitted. Each valve is formed or provided with a stem extending therefrom on both sides and terminating in plungers or pistons 8 which fit and work in stuffing boxes or glands at the ends of the associated bushing. The plungers 8 correspond in cross section with the area of the ports, and hence balance the valves.

As shown in Figs. 2, 4, 6, 8, 9 and 10, a liquid supply pipe 9 communicates through a branching passage 10 with the chambers 6 of the valves 2 and 3. Liquid under sufficient pressure or head for operating the motor, may be supplied by the pump whose action is regulated by the motor, or may be taken from any other available source.

As shown in Figs. 2, 3, 4, 7, 9 and 10, an exhaust pipe 11 leads from a branching passage 12 which communicates with the chambers 6 of the valves 4 and 5 on the opposite side of the case *y*.

As shown in Figs. 6, 7, 8 and 9, the passage *w* communicates through branches with the chambers 7 of the admission valve 2 and of the exhaust valve 4, and as shown in Figs. 6, 7, 8 and 10, the passage *x* communicates through branches with the chambers 7 of the admission valve 3 and of the exhaust valve 5.

As shown in Figs. 2, 3, 4, 5, 9 and 10, at their outer ends or the ends toward which the valves open, the stems of the valves 4 and 5 are pivoted to horizontal levers 13

and 14. These levers are connected as shown in Figs. 2 and 4, by sliding ball and socket joints at one end with the stems of the valves 2 and 3, and at the other end with a vertical lever 15, having a fixed fulcrum 16 midway between them. Midway between the stems of the valves 2 and 3 on the one hand and 4 and 5 on the other hand, the levers 13 and 14 are pivotally connected with a vertical bar 17, as shown in Figs. 4 and 5, and midway between said levers the bar 17 is connected by a horizontal rod 18 with a spring 19 inclosed in a recess of the valve case *y* and tending to close the several valves 2, 3, 4 and 5 and to hold them against their seats.

As shown in Figs. 1, 2 and 3, the lever 15 is connected at its upper end by a link 20 with the lower end of a floating lever 21, which is pivoted in and carried by a two-armed rocker 22, pivotally mounted on the valve case *y*. The upper end of the lever 21 is connected by a link 23 with an arm of the rocker *l*. A two-armed rocker 24 mounted in a stand 25 on the pump frame, 90 has one of its arms connected by a link 26 with the floating lever 21 between its upper end and its connection with the rocker 22, while the other arm may serve as a crank or handle for manually operating the floating lever 21, or may be connected as shown in Figs. 1 and 3, by a rod 27 with a float, piston or other device (not shown) actuated by variations in the head or pressure produced by the pump for automatically imparting the initial movement to the floating lever 21.

In duplex pumps or pumps having two or more plungers which may be actuated by cranks or eccentrics on a common driving shaft, a number of rockers or adjustable fulcrum supports *l* may be operated by a single motor, or by a number of motors, one for each rocker, under the control of a single group of valves like that shown, with branch pipes leading from the pipes *u* and *v* to the cylinders *q* of the several motors.

The pump herein shown and described operates as follows: In Fig. 1 the rocker *l* is shown as adjusted for producing a full stroke of the plunger *b*, so that the pump will operate at its maximum capacity. If under these conditions, the head or pressure produced by the pump is increased on account of a diminished demand, the rocker arms 24 will be turned to the right, as indicated by a dotted line in Fig. 3, by the float or other automatic device acting through the connection 27. The floating lever 21 turning on the pivot connection at its upper end with the link 23 as a fulcrum, will also be swung to the right, as indicated by the dotted line 28, Fig. 3. This movement of the lever 21 will swing the lever 15 to the right, as indicated by the dotted line on the same figure, thereby rocking the levers 13 130

and 14 in opposite directions. The upper lever 13 turning on its pivot connection with the stem of valve 4 as a fulcrum, will lift the admission valve 2 from its seat, as shown 5 in Figs. 8 and 9, thereby admitting fluid under pressure from the supply pipe 9 through the passage 10 and the chambers 6 and 7 of the valve 2, into the passage *w*, and thence by the pipe *u* into the left end of the motor 10 cylinder *q*. At the same time the lower lever 14 turning on its pivot connection with the stem of valve 3 as a fulcrum, will lift the exhaust valve 5 from its seat, as shown in Figs. 7 and 10, releasing the liquid confined in the 15 right end of the motor cylinder *q* through the pipe *v*, passage *w*, chambers 6 and 7 of the valve 5, and passage 12, into the exhaust pipe 11. The motor piston *r* will thus be moved to the right a distance corresponding 20 with the initial movement of the rocker 24, and with the volume of liquid thus admitted through the pipe *u* into the left end of the cylinder 2. The rocker *l* will be turned on its pivots *m* toward the links *i*, carrying the 25 pivots *o* of the links *j* toward the pivot *p* of the links *i*, and correspondingly shortening the stroke of the plunger *b*. This will obviously reduce the volume of liquid delivered by the pump while the crank shaft *c* 30 continues to rotate at a constant speed. The movement of the rocker *l* to the right as above stated, acts through the link 23 to turn the floating lever 21 on its pivot connection with the link 26 as a fulcrum, to the right 35 into the position indicated by the dotted line 29, Fig. 3, thereby turning the lever 15 back to its original position, as shown by full lines in Figs. 1 and 3, and closing the valves 2 and 5. Further admission and release of 40 liquid from the motor cylinder being thus cut off, the piston *r* will be held in the position to which it is moved as above stated, and the pump will continue to operate with a shorter stroke and diminished capacity un- 45 til a further variation in the head or pressure occurs. The valves being balanced by the plungers or pistons 8, will be unaffected by the variations of pressure in the chambers 7 produced by the reaction of the pump 50 plunger *b* on the rocker *l* tending to shift the piston *r* from its position with every reversal of the movement of said plunger. If the head or pressure increases, the rocker *l* will be turned again as above explained, 55 toward the links *i* an interval corresponding with the initial movement of the rocker 24, thus further shortening the stroke of the plunger *b* and reducing the capacity of the pump while the crank shaft *c* continues to 60 rotate at its normal speed. In case of increased demand upon the pump and a consequent lowering of the head or pressure, the rocker arms 24 will be turned to the left and the operations hereinbefore described will be 65 reversed, the lower admission valve 3 and

the upper exhaust valve 4 being opened, admitting liquid under pressure through the pipe *v* into the right end of the motor cylinder *q* and releasing the liquid confined in the left end of said cylinder through the pipe *u*. 70 In this way the stroke of the plunger *b* and the capacity of the pump will be varied according to variations in the demand upon the pump and consequent variations in the head or pressure from full stroke or capacity 75 to zero, and vice versa.

The rocker 24 may be turned by hand, to vary the capacity of the pump, and in that case the floating lever 21 will operate automatically as explained, to close the valves 80 which control the operation of the motor piston *r*.

Various modifications in the construction and arrangement of parts may be made in adapting the invention to pumps of various 85 types for different uses and conditions, without departing from the principle and scope of the invention.

I claim:

1. In a variable capacity pump, the combination with a reciprocating plunger and a driving crank, of an adjustable fulcrum support, a pitman connected at one end with said crank and links of the same length pivotally connected together at one end with 90 the other end of said pitman and at their opposite ends with said plunger and fulcrum support respectively, the pivot connection between the fulcrum support and one link being movable into and out of line with the 95 pivot connection between the plunger and the other link.

2. In a variable capacity pump the combination with a reciprocating plunger and a rotary driving shaft, of an adjustable actuating connection between said plunger and shaft, a motor for changing the adjustment of said actuating connection to vary the stroke of the plunger, and means controlling the operation of said motor comprising a 100 floating lever connected with a part actuated thereby and adapted to automatically stop the motor according to the extent of the initial movement of said controlling means.

3. In a variable capacity pump the combination with a reciprocating plunger and a driving crank, of a movable fulcrum support, a pitman connected at one end with said crank, links of the same length pivotally connected together at one end with 110 the other end of the pitman and at their opposite ends with said plunger and fulcrum support respectively, the pivot connection between the fulcrum support and one link being movable into and out of line with the 115 pivot connection between the plunger and the other link, a motor connected with and adapted to shift said fulcrum support, and means for controlling the operation of said motor. 120 125 130

4. In a variable capacity pump, the combination with a reciprocating plunger and the driving crank, of a rocker having two arms and mounted to swing on an axis transverse of said arms in separate alined bearings, parallel links pivoted at one end thereof to and between the free ends of the rocker arms and of the same length as said arms, a rod connecting the other ends of said links 10 with said crank, and a link connection between and of the same length as said parallel links pivoted at one end to the plunger and at the opposite end to said rod in line with its pivoted connection with said links, 15 the pivot between said rod and links being movable into and out of line with the pivot bearings of the rocker and the pivots between the links and rocker arms being movable into and out of line with the pivot between the link connection and plunger. 20
5. In a variable capacity pump the combination with a reciprocating plunger and a driving crank, of a rocker pivoted to the pump frame, a pitman connected at one end 25 with said crank, and links of the same length pivoted at one end to the other end of the pitman and at their opposite ends to the plunger and rocker respectively, the pivot connection between said rocker and one link being movable into and out of line 30 with the pivot connection between the plunger and the other link. 35
6. In a variable capacity pump the combination with a reciprocating plunger and a driving crank, of a rocker pivoted to the pump frame, links of the same length pivotally connected at one end with the rocker and plunger respectively, a pitman connecting said links at their opposite ends with 40 said crank, the pivot connection between the rocker and one link being movable into and out of line with the pivot connection between the plunger and the other link, a motor connected with and adapted to swing said 45 rocker in opposite directions, and means for reversing and controlling the operation of said motor. 50
7. In a variable capacity pump the combination with a reciprocating plunger and a driving crank, of a rocker pivoted to the pump frame, links of the same length pivoted at one end to the rocker and plunger respectively, a pitman connecting said links at the opposite ends with said crank, a 55 motor connected with said rocker and adapted to swing it in opposite directions, and mechanism for controlling the operation of said motor comprising a floating lever connected with said rocker. 60
8. In a variable capacity pump the combination with a driving crank and a reciprocating plunger, a pitman connected at one end with said crank, a rocker arm pivoted to the pump frame, and links of the same 65 length as the rocker arm pivoted together at

one end to the other end of the pitman and at their opposite ends to the rocker arm and plunger respectively, the pivot between the pitman and the links being in line with the pivot between the rocker and frame when the plunger is at mid stroke, and the pivot between the rocker and one link being movable into line with the pivot between the plunger and the other link to render the plunger motionless while the crank revolves. 70 75

9. In a variable capacity pump the combination with a rotary driving shaft and a reciprocating pump plunger, of an adjustable power transmitting connection between said shaft and plunger, a hydraulic motor 80 for adjusting said connection, liquid supply and exhaust connections with said motor, balanced admission and exhaust valves controlling said liquid connections and arranged in pairs, parallel levers each connected with a pair of admission and exhaust valves, either of each pair of valves serving as a fulcrum for opening the other, a transverse lever fulcrumed between and connected with said transverse levers and adapted 85 when turned in one direction to open one of the admission and one of the exhaust valves and when turned in the opposite direction to open the other admission and the other exhaust valve, and a spring connected with 90 said parallel levers between their connections with said valves and tending to close all of the valves. 95

10. In a variable capacity pump the combination with a rotary driving shaft and a pump plunger, of an adjustable power transmitting connection between said shaft and plunger, a hydraulic motor for adjusting said connection to vary the stroke of the plunger, fluid pressure supply and exhaust 100 connections with said motor, admission and exhaust valves controlling said fluid connections, valve operating mechanism comprising a floating lever adapted when moved in one direction from a neutral position to 105 open one pair of admission and exhaust valves and when moved in the opposite direction from a neutral position to open the other pair of valves, and a connection with said motor adapted to automatically move 110 said lever to a neutral position after initial movement thereof by other means. 115

11. In a variable capacity pump the combination with a driving crank and a pump plunger, of a rocker pivoted to the pump 120 frame, links connected at one end with said plunger and rocker respectively, a pitman connecting the opposite ends of said links with the driving crank, a hydraulic motor connected with said rocker and having fluid 125 pressure supply and exhaust connections, admission and exhaust valves controlling said fluid connections, yielding means tending to close said valves, levers arranged when moved in one direction to open one pair of 130

admission and exhaust valves and when moved in the other direction to open the other pair, a floating lever connected with said valve operating levers and with said 5 motor, and means connected with said floating lever for initially moving it in either direction from a neutral position.

In witness whereof I hereto affix my signature in presence of two witnesses.
